COFFEE MAKER

Oscar L. Lasko, 507 N. Franklin St., West Chester, Pa.

Filed Oct. 28, 1959, Ser. No. 58,105

Term of patent 14 years

(Cl. D44—26)

Fig. 1

Fig. 2

Fig. 3

Fig. 4

Fig. 5

I claim:

The ornamental design for a coffee maker, substantially as shown.
